UNITED STATES PATENT OFFICE.

WILLIAM H. WALDRON, OF NEW BRUNSWICK, NEW JERSEY.

BLOCK-PRINTING MACHINE.

1,145,821.

Specification of Letters Patent.

Patented July 6, 1915.

Application filed June 6, 1914. Serial No. 843,418.

To all whom it may concern:

Be it known that I, WILLIAM H. WALDRON, a citizen of the United States, and a resident of New Brunswick, county of Middlesex, State of New Jersey, have invented certain Improvements in Block-Printing Machines, of which the following is a specification.

One object of my invention is to construct a block printing machine for printing material, such as oil cloth, linoleum, and other fabrics, which are fed intermittently through a machine and in which there is a series of reciprocating block carriers which carry the printing blocks that make the impressions as the material is fed through the machine.

A further object of the invention is to provide means for automatically controlling the block carriers so that any desired block can make an impression at any time.

A still further object of the invention is to construct a machine for printing bordered rugs or mats and similar floor or table coverings.

In the accompanying drawings:—Figure 1, is a plan view in diagram of sufficient of a block printing machine to illustrate my invention; Fig. 2, is a side view in diagram; Fig. 3, is an enlarged side view showing one of the block carriers; Fig. 4, is an enlarged side view of one end of the machine showing the cams for actuating the rods; Fig. 5, is a sectional plan view on the line *a—a*, Fig. 3; Fig. 6, is a transverse sectional view on the line *b—b*, Fig. 3; Fig. 7, is a transverse sectional view on the line *c—c*, Fig. 4; Fig. 8, is a perspective view of one of the cam rods detached; Fig. 9, is a perspective view showing the relation of the three actuating rods and the latch; Fig. 10, is a detached sectional view showing one of the collars and a pin attached; Fig. 11, is a detached sectional view showing three cams secured together ready to be placed in the machine; and Fig. 12, is an outline diagrammatic view of a rug which is made according to my invention.

I will describe in detail a particular form of block printing machine, but other forms may be used without departing from the essential feature of the invention, which is to automatically control the blocks so as to allow them to print at any predetermined time. Furthermore, where the invention is used for printing rugs having an endless

border and where it is desired to make more than one size of rug, the controlling mechanism is so timed that any of a series of blocks can be allowed to make the impression. In the present instance, each block or set of blocks prints the full width of the machine and eighteen inches in length, and the feeding mechanism for the material to be printed is so arranged that said material will move intermittently for eighteen inches, remaining stationary for a sufficient length of time to allow the block to make the necessary impression. Thus I am enabled in one machine to print the body of a rug, where plain centers are duplicated from one to a series of times according to the length of the rug, and to properly print a border section eighteen inches wide, in the present instance at each end of the contemplated rug. The printing blocks are controlled by the automatic mechanism which I will now proceed to describe.

Referring to the drawings, 1 is the frame of the machine consisting of an upper beam 2 and a lower beam 3. This frame is built in the ordinary manner and on the upper beam 2 are vertical guides 4 for the block carriers 5. These block carriers are arranged to reciprocate vertically in the guides and consist of vertical slides 6 at each side of the machine and connecting beams 7 extending from one side of the slide to the other, making the rigid construction which is essential in this type of machine.

8, 9 are the printing blocks, which are detachably secured to the carriers 5 in the ordinary manner. These blocks may be arranged in sets or in one piece as desired, and can be adjusted so that they will print true on the material which is fed intermittently through the machine by endless bands 28 having pins which engage the material.

10, 9 are the inking elements having wheels 10 which travel on rails 11 secured to the frame 1, and these inking elements are connected together by rods 12 and means are provided for reciprocating the rods longitudinally so that the rollers of the several inking mechanisms will pass under the blocks 8 and will ink the projecting surfaces of the blocks. The rollers rotate in the ink fountains, which are made as shown in Figs. 3 and 6.

13 is a cam shaft, one for each block, and these cam shafts are driven in unison and

at the same speed in the present instance. At each end of each cam shaft is a cam 14 having an extension 15, and on the carrier 5 are studs 16 in which are mounted rollers 17 which are engaged by the cam, so that, as the cam rotates, it raises its carrier and the extension 15 insures the return of the carrier to the printing position. There is a long dwell in the cam so as to hold the carrier in the raised position in order to allow the inking mechanism to pass under the printing blocks and to distribute the ink thereon. Projecting from the side of the carrier, in the present instance, is a lug 18 with which engages a latch 19 pivoted at 20 to the frame.

21 is a pivoted keeper which, when turned by hand, will retain the latch in engagement with the lug 18, holding that particular block carrier out of action. This is used when it is desired to dispense with the use of any particular block.

On the latch 19 is an arm 22 having a weight 23 which causes the latch to automatically disengage the block carrier. The cam 14 has a high portion which lifts the carrier above the position of rest so as to allow the latch to move out of engagement with the lug 18. The latch and the lug are beveled so that when the full weight of the carrier is on the latch it will be held in position and can only be released when the carrier is raised.

At each side of the machine, in the present instance, is a series of latch actuating rods or selectors 24; three rods are shown at each side and on each of these rods are collars 25. In the underside of the collars are screw threaded holes adapted to receive detachable pins 26 which are held in position by set screws, Fig. 10, or other fastenings, and on each latch is a pin 27 which projects under the rods at the collars, so that, if there is a pin on any one collar and that particular rod moves forward, the pin 26 will engage the pin 27 of the latch, forcing it into the path of the lug 18 on the carrier 5, and as the carrier leaves the high part of the cam it will be held by the latch until released again by the return movement of the rod 24. The several rods 24 have their bearings in brackets 35 on the frame 1.

36 is a cam shaft at one end of the machine, Figs. 4 and 7, and at each end of this shaft are three cams 37 and on the end of each rod 24 is a head 38 shaped to receive the cam and each head has a roller 39 which bears against the face of the cam, so that each rod is reciprocated according to the particular cut of the cam. The cams only move the rods in one direction in the present instance. A spring 30 on the opposite end of each rod bears against one of the brackets 35 and moves the rod in the opposite direction. An auxiliary spring 31, for the

same purpose, may be used if found necessary, Figs. 2 and 8. The cam shaft 36 controlling the rod is driven from one of the main cam shafts 13, through a shaft 32 by belting, as shown by dotted lines, Figs. 2, 3 and 4. By using the detachable cams 37 and detachable pins 26 the several carriers are under control of the cams and their rods and can be moved into the printing position at any predetermined time.

Referring to Fig. 12, which illustrates in diagram a rug seventy-two inches long, it will take four impressions to print this rug a single color. A single block will make two impressions *x* which will have the body 80 and a portion of the border *y* at each end, while the impressions *w*, *w'* will be the end portions of the rug and will have the end borders *z* and side sections *y'* of the border, and each end will require a separate block. If there are three colors used in printing this rug, then the several portions *x* of the rug will be printed with a set of three blocks, one following the other in the order determined upon by the operator. Then the end *w* of the rug will be printed with three blocks and the opposite end *w'* will also be printed with three blocks, so that it will take nine blocks to print a rug of this type having three colors. If, however, the rug is 95 ninety inches long then there will be three impressions *x* and the same border impressions will be made. Consequently, the same number of blocks, viz., nine, will be required. The same is true when there is only 100 one section *x*, so that a three colored rug of any length desired can be printed with nine blocks. These blocks, by my improved mechanism, can be automatically released so as to print at the proper time as the desired 105 portion of the material comes under the printing block. Thus it will be seen that I provide automatic means for controlling the movement of the printing blocks, so that any block of a series can be controlled to make 110 an impression at the proper time.

I have shown the invention as mechanically operated through rods and cams, but it will be understood that the latches can be actuated by pneumatic or hydraulic mechanism, using a series of cylinders in which are plungers, either directly on the latches or indirectly through the above described rods.

I claim:—

1. The combination in a block printing 120 machine, of a frame; a series of block carriers arranged to reciprocate on the frame to make an impression; inking mechanism; two longitudinal reciprocating selectors arranged to select and hold out of action certain blocks at different times; and means for independently actuating the selectors.

2. The combination in a block printing 125 machine, of a frame, means for intermittently feeding the material; a series of block 130

carriers; printing blocks on said carriers; inking mechanism for the blocks; means for actuating the block carriers; means for retaining the block carriers in the raised position; two cams at one end of the machine; and a rod controlled by each cam and arranged to actuate the means for retaining the block carriers in the raised position.

3. The combination in a block printing machine, of a frame; means for intermittently feeding the material to be printed; a series of block carriers; means for actuating the carriers; printing blocks on the carriers; means for inking the blocks; a latch for each block carrier; a series of rods having pins arranged to engage certain of said latches; and means for actuating said rods whereby the blocks to make the impression can be selected.

20 4. The combination in a block printing machine, of a frame; means for feeding the material intermittently; a series of reciprocating block carriers; printing blocks mounted on the carriers; cams for raising and lowering the carriers; a latch for holding each carrier out of action; inking mechanism for the blocks; a series of longitudinally movable rods having pins engaging one or more of the latches; a spring for moving each rod in one direction; and cams for moving the rods in the opposite direction.

5. The combination in a block printing machine, of a frame; means for feeding material intermittently over the frame; a series of block carriers; a printing block mounted on each carrier; inking mechanism for the blocks; means for vertically reciprocating the block carriers; a latch for holding each block carrier out of operative position; each latch having a projecting pin; a series of rods; means for longitudinally moving said rods; detachable pins secured to the rods and arranged to engage the pins on certain

latches, so that any block carrier can be automatically held out of printing position.

6. The combination in a block printing machine, of a frame; means for intermittently feeding the material to be printed; a series of block carriers; a latch arranged to engage each block carrier to hold it out of action; a cam for actuating each of the block carriers, said cam being so proportioned as to release the carrier from the latch at each upward movement; a series of reciprocating selectors having pins engaging certain of the latches; a transverse cam shaft; independent cams thereon for each reciprocating selector; and means for driving the cam shaft.

7. The combination in a block printing machine, of a frame; means for intermittently feeding the material to be printed; a series of vertically reciprocating block carriers; cams for reciprocating the same; a transverse shaft at each block carrier; a latch at each end of each shaft arranged to directly engage the block carriers; a weight tending to hold the latches out of engagement with the carriers; a series of reciprocating rods mounted in bearings at each side of the machine; collars on the rods; detachable pins carried by the collars; pins on certain of the latches to be engaged by the pins on the rods; a transverse shaft; and cams on each end of this shaft arranged to impart reciprocating motion to the rods, whereby the latches will be forced into engagement with certain of the block carriers and hold them out of action at certain intervals.

In testimony whereof, I have signed my name to this specification, in the presence of two subscribing witnesses.

WILLIAM H. WALDRON.
